PHOTOGRAPHIC PRINTING MACHINE

George C. Garraway, Rutherford, N. J.

Application March 3, 1943, Serial No. 477,810

6 Claims. (Cl. 88—24)

(Granted under the act of March 3, 1883, as
amended April 30, 1928; 370 O. G. 757)

The invention described herein may be manufactured and used by or for the Government for governmental purposes, without payment to me of any royalty thereon.

This invention relates generally to photographic apparatus and more particularly to a machine for automatically making photographic prints by the projection of light rays through a negative onto a strip of sensitized material.

One of the objects of the invention is to provide a photographic machine adapted to produce rapidly enlarged photographic prints of a negative by projection.

Another object of the invention is to provide a photographic machine adapted to project an enlarged image of a negative onto a strip of sensitized material and including means adapted to be operated at predetermined time intervals for causing a plurality of exposures of said negative image to be projected onto the strip of sensitized material for automatically producing a plurality of enlarged photographic prints of the negative thereon, and at the same time the projected image is being printed to cause a grid to be printed on the sensitized material over the projected image, and also to automatically print indicia by contact in the margins of the photographic prints, for designating the lines of the grid.

Another object of the invention is to provide means on the photographic machine for automatically controlling the period of exposures of the photographic prints and means for separately controlling the period of exposures of the indicia printed by contact in the margins of the photographic prints.

Another object of the invention is to provide means on the photographic machine adapted to move automatically the strip of sensitized material a predetermined distance after each exposure of the photographic prints and means for automatically cutting the photographic prints from the strip of sensitized material.

The improved photographic machine may be used for rapidly producing photographic prints from any object, but it is particularly adapted for rapid reproduction of prints of photographic aerial negatives with a grid and marginal indicia designating the lines of the grid produced on the prints, said machine briefly comprising a fixed frame having a roll of sensitized material, a printing portion, a feeding portion and a cutting portion mounted on one end thereof, a photographic projector adjustably mounted on its other end and adapted to project an enlarged image of the negative onto a strip of the sensitized material,

said photographic projector being mounted to move on the frame toward and away from the strip of sensitized material for projecting different enlargements of the negative image onto the strip of sensitized material, a shutter positioned to intercept the negative image projected into the sensitized material, means for automatically operating the shutter at predetermined time intervals for causing a plurality of exposures of the negative image to be projected onto the strip of sensitized material for producing a plurality of enlarged photographic prints thereon, means for automatically cutting the photographic prints from the strip of sensitized material, outer and inner frames mounted in front of the strip of sensitized material, said inner frame adjustably mounted vertically on said outer frame, a grid, transparent members having indicia thereon and a plurality of lamps mounted on the inner frame, electrical means for energizing said lamps for exposing the indicia to the strip of sensitized material, whereby said indicia is printed on the strip of sensitized material, said indicia designating the lines of the grid, means for automatically actuating said outer frame at predetermined time intervals toward the strip of sensitized material during each exposure of the negative image for contacting the grid and transparent members having the indicia thereon with the strip of sensitized material and for moving the outer frame away from the strip of sensitized material to move the grid and indicia out of contact with the strip of sensitized material after each exposure, means for actuating said electrical means at predetermined time intervals for energizing said lamps during the contacting period of the indicia with the strip of sensitized material, automatically operated means including a feed roller and take-up rollers for moving the strip of sensitized material a predetermined distance after each exposure toward the cutting means, and means including an adjusting roller contacting with the strip of sensitized material and adapted to be adjusted on the feed roller to cause the distance from an upper edge of a photographic print to the cutting means to be a multiple of the size of the photographic print on the strip of sensitized material.

With the above and other objects and advantages in view, the invention consists of certain features of construction and operation of parts which will hereinafter be described and shown in the accompanying drawings, in which—

Fig. 1 is a side elevation of the improved photographic printing machine including a fixed lon-

itudinally extending frame having a printing portion, a roll of sensitized material, a cutting portion, and a portion for feeding a strip of sensitized material toward the cutting portion on one end thereof and a photographic projector adjustably mounted longitudinally on the frame adjacent to the other end thereof and adapted to project an enlarged image of a negative onto the strip of sensitized material;

Fig. 2 is a top plan view thereof;

Fig. 3 is an enlarged fragmentary view of one side of the printing, cutting and feeding portions of the machine having a roll of sensitized material mounted on one end of the frame;

Fig. 4 is an enlarged rear end view of the printing, cutting and feeding portions of the machine with the roll of sensitized material removed therefrom;

Fig. 5 is an enlarged fragmentary perspective view of the printing, cutting and feeding portions of the machine having a strip from the roll of sensitized material in operative position thereon;

Fig. 6 is an enlarged fragmentary view, partly in section, of the other side of the printing, cutting and feeding portions of the machine;

Fig. 7 is an enlarged fragmentary longitudinal sectional view of the machine taken on the line 7-7 of Fig. 6;

Fig. 8 is an enlarged fragmentary front view of the printing, cutting and feeding portions of the machine;

Fig. 9 is an enlarged fragmentary, longitudinal sectional detail view, partly in elevation, of a portion of a mechanism including rollers and a friction clutch for taking up any slack in the strip of sensitized material from the feeding portion of the machine to the cutting portion;

Fig. 10 is an enlarged fragmentary detail sectional view of a part of a mechanism for adjusting the distance of the strip of sensitized material from the feeding portion of the machine to the cutting portion;

Fig. 11 is an enlarged fragmentary detail view of another portion of a mechanism including a main shaft having a one-revolution clutch shown in section mounted thereon;

Fig. 12 is a cross-sectional view taken on the line 12-12 of Fig. 11 with parts broken away;

Fig. 13 is an enlarged fragmentary perspective view of frame members partly in section having a carrier frame movably mounted thereon with means for actuating the carrier frame toward and away from the frame members and including other operative parts of the machine used in carrying out the invention;

Fig. 14 is an enlarged fragmentary detail view of a shutter and connected parts;

Fig. 15 is an enlarged fragmentary detail view of a portion of the feed roller and distance adjusting mechanism;

Fig. 16 is an enlarged detail sectional view partly in elevation of a means for locking on and unlocking a roll of sensitized material from the machine;

Fig. 17 is an enlarged fragmentary sectional detail view, partly in elevation, of an overrunning clutch and connected parts used in carrying out the invention;

Fig. 18 is a fragmentary end view of the overrunning clutch taken on the line 18-18 of Fig. 17;

Fig. 19 is a front view of a transparent element having a letter thereon adapted to be printed on the strip of sensitized material for designating a line of a grid;

Fig. 20 is a wiring diagram showing the electrical connections; and

Fig. 21 is a fragmentary view of a portion of the strip of sensitized material having prints of a photographic aerial map negative produced thereon including a grid and indicia in the form of letters designating the grid lines printed on the marginal edges of the photographic prints.

Referring more particularly to Figs. 1 and 2 of the drawings, 1 designates a longitudinally extending supporting frame including upper and lower longitudinally extending frame members 2 and 3, respectively, and upright frame members 4 and 5. A photographic projector portion 15 of the improved photographic printing machine is mounted on the upper longitudinally extending frame members 2 adjacent to one end of the supporting frame 1 and printing, cutting and strip feeding portions B, C and D, respectively, are mounted on the other end thereof. The photographic projector portion A may include any suitable type of projector but for purposes of illustration is shown as being of the type illustrated in the copending application Serial No. 471,055, filed January 1, 1943, wherein a vertically extending lamp housing 6 containing a light source 7 is mounted on a horizontally extending carrier 8 for a negative 9, with said negative carrier 8 being longitudinally adjustably mounted on a pair of longitudinally extending tubular members 10. An extensible bellows 11 of an enlarging camera 12 extends vertically downward from the negative carrier 8 and has enlarging lenses 13 mounted on its lower end, together with an image projection prism or mirror 14 arranged at a right angle to the main optical axis of the photographic projector for projecting an image of the negative 9 outwardly in a horizontal direction onto strip of sensitized material 15 operatively arranged on the machine with its width extending transversely of the supporting frame 1. Upon actuating the photographic projector longitudinally in a forward direction away from the strip of sensitized material 15 on the supporting frame 1 by means of a mechanism including a hand wheel 16, the extensible bellows 11 is caused to be moved upwardly in a vertical direction by means of a mechanism including rollers 17 which are adapted to ride on the upper edges of upwardly curved cam members 18 to collapse the bellows for producing different enlargements of predetermined ratios or various enlargements having different degrees of magnification of the negative 9 on the strip of sensitized material 15 and upon moving the photographic projector longitudinally in a rearward direction the lower end of the extensible bellows 11 is caused to move downwardly in a vertical direction for other enlargements of the negative. Reference may be had to the above mentioned application for more detailed description of the photographic projector illustrated.

The enlarged image of the negative 9 is caused to pass through an automatically operated shutter 19 of conventional construction shown in detail in Fig. 14 and including a pair of leaves 19' actuated by an outwardly extending arm 20 connected at its outer end with one end of a Bowden wire 20', the other end of which Bowden wire is connected with a plunger 21 actuated by a solenoid 22 of an electromagnet 23 connected in an electrical circuit (Fig. 20) to be hereinafter described, and enclosed within a housing 24 mounted on one of the upper longitudinally ex-

tending frame members 2 of the supporting frame 1, Figs. 1 and 5.

The strip 15 of sensitized material is part of a roll 25 thereof, the ends of which roll are adapted to be mounted on the inner ends of shafts 26 and 26' rotatably mounted in bearings 27 fixedly mounted on the outer ends of outwardly extending brackets 28 which in turn are mounted on the upright frame members 4 of the supporting frame 1, Figs. 2 and 4. The shaft 26 is adapted to be moved on its bearing out of engagement with one end of a used roll of sensitized material for replacing a new roll of sensitized material on the shafts 26 and 26', and in order to hold the shaft 26 in its operative position against the roll of sensitized material and to move it out of engagement therewith, a holding device shown in detail in Fig. 16 including an arm 29 having an aperture 30 formed therein adjacent to the upper end thereof and movably mounted at its lower end in an aperture 31 formed in an outwardly extending portion 32 on the lower end of a downwardly extending bracket 33 provided on a bearing 34. An expansion spring 35 is provided having one end abutting against the bearing 34 and its other end pressing outwardly on the arm 29. The outer end of the shaft 26 extends through the aperture 30 of the arm 29, which aperture 30 is of a larger diameter than the diameter of the shaft whereby, upon the spring 35 pressing outwardly on the arm 29, the arm is caused to engage the shaft 26 and frictionally hold it in a rotative and operative position. By pushing inwardly on the upper end of the arm 29 against the action of the spring 35, the shaft 26 may be pulled outwardly for disengaging it from one end of a used roll of sensitized material to remove the used roll whereby a new roll of sensitized material may be placed on the machine. A brake shoe 36 is adapted to bear against the roll of sensitized material for providing the required tension thereon, which brake shoe 36 is pivotally connected at 37 on the outer ends of arms 38 pivotally connected at their inner ends to the upright frame members 4 at 39 of the supporting frame 1.

In placing the strip 15 of sensitized material from the roll 25 in an operative position on the photographic machine for automatically producing prints thereon, it is first brought under a roller 40 mounted on the outer ends of supporting arms 41 pivotally mounted at their inner ends at 42 on brackets 43 mounted on the rear edges of the upright frame members 5 at 44 of the supporting frame 1. The strip 15 is then brought over a roller 45 mounted on the arms 41 intermediate their ends. The arms 41 are movably mounted in bearings 46 slidably mounted on vertically extending rods 47 having expansion springs 48 provided thereon with the lower ends of the springs 48 bearing against the lower frame members 3 of the supporting frame 1 and their upper ends pressing against the bearings 46. Adjusting nuts 49 are threadedly mounted on the upper ends of the rods 47 for raising and lowering the ends of the rollers 40 and 45 horizontally on the rods whereby, should the strip of sensitized material tend to travel other than in a straight line from the roll 25, the direction of movement thereof may be corrected. From the roller 45 the strip of sensitized material is brought under a roller 50 mounted on brackets 51 on the front edges of the upright frame members 5 and, from the roller 50, the strip is brought

vertically upward in contact with the front surface of a transversely and vertically arranged plate 52 mounted on and in spaced relation from the front edges of the upright frame members 5 by means of bolts 53. The strip of sensitized material is then placed over a feed roller 54, the shaft 55 of which is mounted in bearings 56 mounted on the upper surfaces of short longitudinally extending frame members 57 on the upper ends of the upright frame members 4 and 5 and from the feed roller 54, the strip passes under an adjusting roller 58 of a distance adjusting mechanism, indicated generally by E, to between a pair of rubber covered take-up rollers 59 and 59' and then is inserted between a stationary blade 60 and a movable blade 61 of a conventional shearing device of the cutting portion C of the machine.

The pair of take-up rollers 59 and 59' are provided for taking up any slack in the strip of sensitized material from the feed roller 54 to the blades 60 and 61 of the shearing device and are mounted to rotate in contact with each other. The roller 59 is rotatably mounted in downwardly extending bearings 62 and 62' formed on brackets 63 and 63' fixedly mounted on the upper surface of a transversely extending beam 64 of the shearing device, which beam 64 is mounted on the frame members 57. The take-up roller 59 has an elongated shaft portion 65 on one end, which extends through the bearing 62 of the bracket 63 shown in detail in Fig. 9. A friction clutch 66 is mounted on the shaft portion 65, which clutch 66 includes a disk 67 on one end of a collar 68 fixedly secured adjacent to the bearing 62 and a disk 69 slidably mounted on the shaft portion 65. The disk 69 is provided with an outwardly extending collar 70 having a small sprocket wheel 71 on the outer end thereof which is engaged by the inner end of a spring 72 mounted on the shaft portion 65. A hand adjusting nut 73 is threadedly mounted on the outer end of the shaft portion 65 and adapted to bear against the outer end of the spring 72 which is forced inwardly to bear against the sprocket wheel 71 whereby the disk 69 is adapted to engage frictionally the disk 67 for a purpose which will hereinafter appear. The take-up roller 59' is placed on top of the take-up roller 59 and is rotatably mounted at its ends in rectangular shaped bearings 74 slidably mounted in vertically extending slots 74' formed in the brackets 63 and 63'. The upper ends of the slots 74' are closed by plates 75 and expansion springs 76 are provided in the slots between the plates 75 and bearings 74, whereby the upper take-up roller 59' is pressed into contact with the lower take-up roller 59. The small sprocket wheel 71 is driven by a sprocket chain 77 driven by a large sprocket wheel 78 fixedly mounted on one end 79 of the feed roller shaft 55. Gears 59'' meshing with each other are provided on the other ends of the takeup rollers 59 and 59' from the friction clutch 66.

The adjusting roller 58 of the distance adjusting mechanism E bears against the strip of sensitized material 15 on the feed roller 54 and is mounted on the outer ends of arms 80, the inner ends of which arms 80 are pivotally mounted on the upper ends of arms 81 pivotally mounted at their lower ends on the ends of the feed roller shaft 55. Adjacent to the ends of the feed roller 54 are vertically extending arcuate-shaped members 82 having teeth 83 on their upper edges and

fixedly secured to the upper surfaces of the frame members 51. A shaft 84 having reduced end portions 85 is rotatably mounted on the rocker arms 81, which reduced end portions 85 extend through the arms 81 and have pinions 86 fixedly mounted thereon meshing with the teeth 83 of the arcuate-shaped members 82. The ends of the shaft 84 adjacent to the reduced end portions 85 thereof have locking nuts 87 threadedly mounted thereon which are adapted to be threaded outwardly for engagement with the inner surfaces of the arms 81 for preventing rotation of the shaft 84 and hence hold the pinions 86 in a locked position on the arcuate-shaped members 82, whereby the adjusting roller 58 is held in its adjusted position on the feed roller 54. Upon loosening up on the adjusting nuts 87 on the ends of the shaft 84 in a direction away from the arms 81, the shaft 84 may rotate, thus permitting the pinions 86 to move around on the arcuate-shaped members 82 in mesh with the teeth 83 thereof for adjusting the roller 58 on the feed rollers 54 to vary the distance of the strip of sensitized material 15 from the feed roller 54 to the blades 60 and 61 of the shearing device for a purpose which will hereinafter appear. Springs 88 are connected between the arms 80 and 81 for holding the adjusting roller 58 in contact with the sensitized material on the feed roller 54.

A conventional overrunning clutch 89, shown in detail in Fig. 17, is mounted on the opposite end of the feed roller shaft 55 from the sprocket wheel 78, said clutch comprising a hub 90 keyed to the feed roller shaft 55 and provided with a plurality of flat surfaces 91 having rollers 92 movably mounted thereon engaged by a race 93 in a housing 94 which carries a gear 95 meshing with the upper end of a rack 96 slidably mounted in a bracket 97 mounted on the feed roller shaft 55. The lower end of the rack 96 is pivotally mounted on a crank pin 98 having an enlarged head 99 formed on its inner end which is adjustably mounted on a threaded shaft 100 rotatably mounted on end plates 101 of a pair of parallel bars 102 and 102' of a crank 103 which is fixedly mounted on one end of a main shaft 104 rotatably mounted in bearings 104' mounted on the upright frame members 5. The crank pin 98 has an enlarged portion 98' formed thereon adjacent to its head 99, which enlarged portion 98' carries an index 105 for a suitable graduated scale 106 on the bar 102 of the crank 103 and the lower end of the rack 96 is pivotally held on the outer end of the crank pin 98 by a nut 107. One end of the threaded shaft 100 has a tool engaging portion 108 formed thereon which is adapted to be engaged by a wrench or other suitable device for rotating the shaft whereby the crank pin 98 may be adjusted therealong for adjusting the lower end of the rack 96 on the crank 103 with the index 105 indicating on the scale 106 the amount of adjustment of the lower end of the rack on the crank 103 for a purpose which will hereinafter appear.

A vertically arranged outer carrier frame 109 is operatively mounted on the frame members 5 in front of the plate 52, which frame 109 is preferably of a rectangular formation, including a pair of upright side members 110 and 110' having horizontally extending upper and lower end pieces 111 thereon. An inner frame 112 is adjustably mounted to be mover vertically on the carrier frame 109, said inner frame 112 including horizontally extending upper and lower end portions

113 and vertically extending portions 114 having strips 115 provided thereon, the longitudinal side edges 116 of which strips extend outwardly from the longitudinal side edges of the vertically extending portions 114 of the inner frame 112 and slidably engage in vertically extending guideways 117 formed on the inner surfaces of the upright side members 110 and 110' of the carrier frame 109. A grid 118 of fixed dimensions, having horizontally and vertically arranged wires or lines 122 of suitable thickness, and a plurality of light apertures 119 are provided on the inner frame 112, which light apertures 119 are in spaced formation around the inner frame 112 and are closed at their inner ends by any suitable transparent material which may be in the form of tabs 120, Figs. 7 and 19, having indicia which may be in the form of letters 121 or other data provided thereon designating the lines 122 of the grid 118. The apertures 119 are closed at their outer ends by lamp housings 123 which are mounted on the outer surface of the inner frame 112 in any suitable light-proof manner. The lamp housings 123 have lamps 124 therein which are mounted in the lamp sockets 125, grounded at one side at 126 to the frame 1 and connected with a ring bus 127 by conductors 128, which ring bus 127 is in turn connected to one end of a secondary winding 129 of a transformer 130, which secondary winding 129 is grounded at its other end at 131, Fig. 20.

The inner frame 112 is adjustable vertically on the carrier frame 109 by means of racks 132 and pinions 133, which racks 132 are mounted on the lower ends of the upright side members 110 and 110' of the carrier frame 109. The pinions 133 mesh with the racks 132 and are mounted on the ends of a shaft 134 rotatably mounted on outwardly extending ears 135 on the inner frame 112. Hand knobs 136 are provided on the shaft 134 for rotating the shaft for moving the pinions 133 on the racks 132. The lower end portion 113 of the inner frame 112 has spaced pins 137 extending vertically downward therefrom, which pins 137 are slidably mounted in bearings 138 mounted on the lower end piece 111 of the carrier frame 109. Adjusting screws 139 provided on the bearings 138 are adapted to be actuated for engaging the pins 137 to hold the inner frame 112 in an adjusted position on the carrier frame, and vertically arranged springs 140 having their upper ends suitably secured to the upper ends of the side members 110 and 110' of the carrier frame 109 and their lower ends suitably secured to the inner frame 112 whereby the inner frame 112 may be balanced on the carrier frame. The upright side members 110 and 110' of the carrier frame 109 have inwardly extending brackets 141 and 141', respectively, provided adjacent to the upper and lower ends thereof, which brackets 141 and 141' are connected together at their outer ends by rods 142 and 142', respectively. Bell cranks 143 and 143' are pivotally mounted at one of their ends on the ends of the rods 142 and 142' adjacent to the outer ends of the brackets 141 on the side member 110 of the carrier frame 109, and straight cranks 144 are pivotally mounted at one of their ends on the ends of the rods 142 and 142' fixed to the brackets 141' on the side member 110' of the carrier frame. The bell cranks 143 and 143' and the other ends of the straight cranks 144 are fixedly mounted on rods 145 pivotally mounted in bearings 145' on the upright frame members 5 of the fixed frame 1. The bell crank 143 on the lower end 75 of the upright side member 110 of the carrier

frame 109 is pivotally connected at its outer end to the lower end 146 of a connecting rod 146' which extends vertically upward through the outer end of a plate 147 mounted on a short longitudinally extending side frame member 148, with the upper end of the connecting rod 146' having a bifurcated fitting 149 provided thereon pivoted to the outer end 150 of the bell crank 143' on the upper end of the upright side member 110 of the carrier frame. A spring 151 is mounted on the connecting rod 146' between the bifurcated fitting 149 and the plate 147 for forcing the connecting rod in an upward direction during certain periods in the operation of the machine. The bifurcated fitting 149 carries a roller 152 which contacts with a cam 153 having a low part 154 and a high part 155 thereon, which high part 155 is adapted to actuate the connecting rod 146' in a downward direction for a purpose which will hereinafter be described. The cam 153 is fixedly mounted on the main shaft 104 adjacent to one end thereof, which main shaft 104 also has additional cams 156 and 157 fixedly mounted thereon, together with a conventional one-revolution clutch 158. The main shaft 104 is driven in a counter-clockwise direction through the one-revolution clutch 158 by means of a conventional reduction geared electric motor 159 which drives a sprocket wheel 160 connected by a sprocket chain 161 to a sprocket wheel 162 on one end of the clutch 158. The cam 156 is eccentrically mounted on the opposite end of the main shaft 104 from the cam 157 and has a roller 163 contacting therewith, which roller 163 is mounted on one end 164 of a lever 165 fixedly mounted at 166 to a rock shaft 167 rotatably mounted in bearings 168 on the frame members 4. One end of a lever 169 is fixedly connected to an outer end of the rock shaft 167, the other end of which lever 169 is pivoted at 170 to one end of a link 171, with the other end of the link 171 pivoted at 172 to a bell crank 173 pivotally mounted at 174 on a bracket 175 provided on one end of the beam 64. The bell crank 173 and a connecting rod 176 are adapted to actuate one end of the movable cutting blade 61 toward and away from the stationary cutting blade 60 of the conventional shearing device through a linkage mechanism, including parts 177 and 177' mounted on the brackets 175 and 178, respectively, which linkage part 177' and bell crank 173 are connected together by rods 179 and 180 having an expansion spring 181 provided thereon for returning the movable cutting blade 61 to its inoperative position.

The one-revolution clutch 158, Figs. 11 and 12, may be of any suitable conventional type, but for purposes of illustration is shown as being of the type manufactured by the Hilliard Corporation (Bulletin No. 139, October 25, 1937), wherein upon the clutch being engaged hardened rolls 182, which act as wedges between an outer race 183 and flat surfaces 184 on the inner hub 185, transmit the drive from the outer clutch housing 186 to the inner hub 185 and the main shaft 104. The cage 187 holding the rolls 182 extends to the left and the trip cam 188 is connected with the cage by pin 189 and piece 190. Thus, when the trip cam 188 is moved, the cage 187 and rolls 182 move also. The tension spring 191 holds the trip cam 188, cage 187 and rolls 182 in the proper position to engage the clutch. The trip cam 188 has a shoulder 192 formed thereon which is adapted to be engaged by the inner end 193 of a lever 194 for releasing the

clutch from the main shaft 104, which lever 194 is pivotally mounted at 195 on a bracket 196 mounted on a support 197 which in turn is mounted on the frame members 148 and 148'. The inner end 193 of the lever 194 is held in contact with the trip cam 188 of the clutch 158 by a leaf spring 198 and the other end 199 of the lever has a plunger 200, Fig. 20, pivotally connected thereto, which plunger 200 is adapted to be actuated by a solenoid 201 of an electromagnet 202 mounted on a U-shaped bracket 203 of the support 197, with the solenoid 201 being connected by a conductor 204 at 205 with an electrical circuit, Fig. 20, to be hereinafter described.

The cam 157 on the main shaft 104 has a lobe 206 formed thereon which is adapted to contact with a roller 207 mounted on the outer free end of a spring arm 208 adapted to be actuated for actuating two conventional micro switches 209 and 209' contained within a housing suitably mounted on the upright frame member 5, Figs. 5 and 13. A conventional counter 210 is provided for counting the number of photographic prints produced by the machine, which counter 210 is mounted on the longitudinally extending frame member 2 and connected in circuit with the shutter 19 in the electric circuit, Fig. 20.

An electrical housing 211 is mounted on one side of the fixed frame 1 and has a panel 212 provided thereon which carries two commercial electrically operated timing units 213 and 214, also light, shutter, contact printing and motor switches 215, 216, 217 and 218, respectively, and an electric socket 219 adapted to be engaged by an electric plug 220 connected to a suitable source of electrical supply (not shown) by conductors 221, Fig. 20.

Referring more specifically to Fig. 20, the electric motor 159 is connected to the positive and negative sides of the electrical circuit by means of conductors 222 and 223 through the motor switch 218, and the light source 7 of the photographic projector A is connected at 224 to the conductor 222 of the positive side of the circuit by conductor 225 and to the conductor 223 of the negative side of the circuit at 226 through the light switch 215 by the conductor 225'. The solenoid 22 of the electromagnet 23 for actuating the plunger 21 which in turn actuates the Bowden wire 20' for actuating the shutter 19 is connected by a conductor 227 to the conductor 222 at 228 and the other end of the conductor 227 is connected to the shutter switch 216 which is adapted to engage with a contact 229 on one end of a conductor 230 when the photographic machine is operated to hold the shutter 19 open and to engage with a contact 231 on one end of a conductor 232 connected to the conductor 223 leading to the negative side of the circuit. The other end of the conductor 230 is connected to a contact 233 adapted to be engaged by an armature 234 of a relay 235 of the commercial electrically operated timing device 213 adapted to control the projection exposure time. The armature 234 is connected by a conductor 236 to a conductor 237, one end of which conductor 237 is connected to the electromagnet 238 of the relay 235, with the other end of the conductor 237 being connected to a contact 239 of the micro switch 209. The other contact 240 of the micro switch 209 is connected by a conductor 241 to a conductor 242 which in turn is connected at 243 with the conductor 223. The electromagnet 238 of the relay 235 is connected with the electromagnet 244 of a relay 245

by a conductor 246 connected to the conductor 237 at 247. The other contact 248 of the relay 235 is adapted to be engaged by the armature 234 which is normally held in an open position by a spring 249 and is connected by the conductor 204 to the solenoid 201 for actuating the plunger 200 mounted on the outer end of the lever 194 which is adapted to engage the shoulder 192 of trip cam 188 on the one-revolution clutch 158 at its inner end 193 for releasing the clutch from the main shaft 104. The solenoid 201 is connected by the conductor 204 to a conductor 250 at 205, which conductor 250 is connected at one end 251 to the conductor 222 and at its other end to a contact 253 which is adapted to be engaged by an armature 254 of a relay 255. The armature 254 is normally held in engagement with the contact 253 by a spring 156 and is connected by a conductor 257 to a contact 258 of an electrically operated timing element 259 of the commercial electrically operated timing device 213. The switch arm 260 of the timing element 259 is connected by a conductor 261 to the conductor 246 at 262 and is adapted to contact at predetermined time intervals with the contact 258 for completing the circuit through the conductors 257 and 261. The electromagnet 263 of the relay 255 is connected by a conductor 264 to the conductor 204 at 265 and to the switch arm 266 of a master control electrically operated timing element 267 of the timing device 213, which switch arm 266 is adapted to contact at predetermined time intervals with the contact 268 connected by a conductor 269 with the conductor 250 at 270. The armature 271 of the relay 245 is connected by a conductor 272 to the conductor 246 at 273 and is adapted to engage a contact 274 connected by a conductor 275 to the conductor 223 at 276. The commercial electrically operated timing device 213 is provided with a hand indicator 277 which is adapted to be adjusted along the scale 278 on the plate 279 by a hand knob 280 for changing the timing of the device 213 in a manner well known in the art.

A solenoid 281 is connected by a conductor 282 across the conductor 227 having the solenoid 22 for actuating the plunger 21 for actuating the shutter 18, which solenoid 281 is adapted to actuate a plunger 283 adapted to actuate the conventional counter 210 for counting the number of prints produced by the machine.

An electromagnet 284 of a relay 285 of the commercial electrically operated timing unit 214 for controlling the contact printing time of the indicia on the sensitized material is connected by a conductor 286 to a contact 287 of the contact printing switch 217, which switch 217 is connected by a conductor 288 to a contact 289 of the micro switch 209', the other contact 290 of the micro switch 209' being connected to the end of the conductor 242 connected at 243 to the conductor 223. An armature 291 is adapted to be actuated by the electromagnet 284 of the relay 285, which armature 291 is connected by a conductor 292 to the conductor 286 and is adapted to engage a contact 293 connected to a conductor 294 which has the primary winding 295 of the transformer 130 in circuit therewith and connected to the conductor 222 at 296. One end of the secondary winding 129 of the transformer 130 is connected to the bus 127 of the contact printing portion of the machine with the other end of the secondary winding being grounded at 131. The electromagnet 284 of the relay 285 is also connected by a conductor 297 to a contact 298 which is adapted

to be engaged by an armature 299 of a relay 300, the electromagnet 301 of which is connected by a conductor 302 to the conductor 286 and to a switch arm 303 of a timing element 304 of the commercial electrically operated timing device 214, which switch arm 303 is adapted to contact with the contact 305 connected by a conductor 306 with the conductor 250 at 307. The armature 299 is normally held in an open position by a spring 308 and is connected by a conductor 309 to the conductor 306. The commercial electrically operated timing device 214 is provided with a hand indicator 310 which is adapted to be adjusted along the scale 311 by a hand knob 312 for changing the timing of the device in a manner well known in the art.

In automatically making photographic prints by the improved photographic printing machine, assuming that the electrical socket 219 has been engaged by the plug 220 for connecting the electrical circuit, Fig. 20, with a source of electrical supply, by closing the light switch 215 a circuit is completed from the positive side of the circuit through the conductor 222, conductor 225 through the lamp 1, light switch 215 and conductor 225' to the negative side of the circuit, thereby energizing the lamp 1 and producing a source of illumination in the lamp housing 8 of the photographic projector A, and also assuming that the shutter switch 218 has been moved upwardly to engage the contact 231 whereby a circuit is completed from the conductor 222 through the conductor 227 including the solenoid 22 of the electromagnet 23 adapted to actuate the plunger 21 connected to the Bowden wire 20' which in turn actuates the leaves 19' of the shutter 18 to an open position, then through the conductor 232, to the conductor 223, to the negative side of the circuit.

By energizing the lamp 1 the photographic projector A is adapted to project an image of the negative 9 outwardly in a horizontal direction through the shutter 18 onto the portion of the strip of sensitized material 15 in front of the plate 52 of the printing portion B of the machine, and by actuating the projector A longitudinally in either direction on the frame 1 different enlargements of predetermined ratios or various enlargements having different degrees of magnification of the negative may be projected onto the strip of sensitized material, which different enlargements of predetermined ratios may be determined by the device 313, Fig. 1, in a manner disclosed in the pending application Serial No. 471,055, filed January 1, 1943, above referred to.

Upon obtaining the desired enlargement of the negative image projected onto the sensitized material, the motor switch 218 is closed, thus completing a circuit through the conductor 222 to the motor 159 and from the motor to the negative side of the circuit by conductor 223, whereby the motor 159 is caused to rotate which rotates the one-revolution clutch 158 in a counter-clockwise direction through the sprocket wheels 160 and 162 and chain 161, whereby the main shaft 104 is rotated in a counter-clockwise direction rotating the cams 153, 156 and 157 in the same direction. As the cam 153 is revolved, the roller 152 on the bifurcated fitting 149 on the upper end of the connecting rod 146' is caused to ride up on the high part 155 of the cam which forces the connecting rod 146' in a downward direction against the action of the spring 151. The connecting rod 146' pushes downwardly on the outer end of the arm of the bell crank 143 and pulls

downwardly on the outer end 150 of the bell crank 143', rotating the bell cranks 143 and 143' which in turn rotate the rods 145 in a clockwise direction and causing the other ends of the arms of the bell cranks pivoted to the rods 142 and 142' adjacent to the brackets 141 to pull inwardly on the brackets 141. Upon the rotation of the rods 145 by the bell cranks 143 and 143', the upper ends of the straight cranks 144 are caused to pull inwardly on the brackets 141' whereby the carrier frame 109 carrying the inner frame 112 having the contact printing indicia 121 thereon, including the grid 118, is caused to be moved inwardly toward the plate 52 until the grid 118 on the inner frame and the transparent tabs 120 having the indica 121 thereon designating the grid lines 122 contact with the portion of the strip of sensitized material 15 in contact with the front of the plate 52.

By moving the shutter switch 216 downwardly into engagement with the contact 229 and closing the contact printing switch 217, upon the transparent tabs 120 and grid 118 contacting with the sensitized material, the switch cam 157 has been rotated sufficiently to cause its lobe 206 to contact with the roller 207 of the switch arm 208, whereupon the switch arm 208 is caused to be moved inwardly for actuating the micro switches 209 and 209' into engagement with their contacts 239-240 and 289-290, respectively, whereby current is caused to flow from the conductor 222 through the conductor 227 through the solenoid 22 of the electromagnet 23 for actuating the plunger 21 which in turn is adapted to actuate the Bowden wire 20' for operating the leaves 19' of the shutter 19 to an open position. The circuit is completed through the shutter switch 216, conductor 230, the armature 234 of the electromagnet 238 of the relay 235, conductors 236 and 237, through the micro switch 209, conductors 241 and 242 to the negative side of the circuit through conductor 223, thereby operating the shutter 19 to an open position.

A circuit is also completed from the conductor 222 through the conductor 250, armature 254 of the relay 255, conductor 257 through the switch arm 260 of a timing element 259 of the conventional electrically operated timing device 213, conductor 261, then through the electromagnet 238 of the relay 235, conductor 231, the micro switch 209, conductors 241 and 242 to the negative side of the circuit through the conductor 223. The current is also caused to flow from the conductor 261 through the conductor 246 through the electromagnet 244 of the relay 245 to the conductor 237 and through the micro switch 209, conductors 241 and 242 and to the negative side of the circuit through conductor 223.

After a predetermined time interval, which time interval may be set by adjusting the hand indicator 277 by means of the knob 280 along the scale 278 on the conventional electrically operated timing device 213, the switch arm 266 of the timing element 267 is caused to engage the contact 268 whereby a circuit is completed from the conductor 250, conductor 269 through the timing element 267, conductor 264, through the electromagnet 263 of the relay 255 to the conductor 204.

The micro switches 209 and 209' and the contact printing switch 217 being closed, a circuit is completed from the conductor 250 to the conductor 306, through the conductor 309, the armature 299, of the relay 300, conductor 297

through the electromagnet 284 of the relay 285 of the timing unit 214, and from the electromagnet 284 to the conductor 286 through the contact printing switch 217, conductor 288, through the micro switch 209' to the conductor 242 and conductor 223 to the negative side of the circuit. A circuit is also completed from the conductor 222, through the conductor 294 including the primary winding 295 of the transformer 130, through the armature 291, conductor 292 to the conductor 286 through the contact printing switch 217, conductor 288, micro switch 209', conductor 242 and conductor 223 connected to the negative side of the circuit. Another circuit may also be completed from the conductor 250 through conductor 306 through the switch arm 303 of the timing element 304 of the conventional electrically operated timing device 214, and from the switch arm 303 to the conductor 302 through the electromagnet 301 of the relay 300 to the conductor 286. The primary winding 295 of the transformer 130 being energized, current is caused to flow in the secondary winding 129 for lighting the lamps 124 through the ring bus 127, whereupon the indicia 121 is printed by contact in the margins of the photograph prints of the negative image projected onto the sensitized material, said indicia 121 designating the lines 122 of the grid 118 which has been also printed on the sensitized material. The time of exposure of the indicia 121 on the sensitized material may be regulated by the electrically operated timing device 214 by adjusting the hand indicator 310 by the knob 312 along the scale 311.

Upon the electromagnet 238 of the relay 235 and the electromagnet 244 of the relay 245 being energized, the armature 234 of the relay 235 is pulled downwardly, breaking the circuit through the solenoid 22 of the electromagnet 23, whereby the shutter 19 is caused to close, actuating the counter 210 which is connected by the conductor 282 in circuit with the conductor 227 and shielding the sensitized material from the negative image from the photographic projector A, and the armature 271 of the relay 245 is pulled upwardly into engagement with the contact 274 whereby a circuit is completed from the conductor 275 through the conductor 223 to the negative side of the circuit. By actuating the armature 234 by the electromagnet 238 of the relay 235 into engagement with the contact 248, a circuit is completed from the conductor 250 through a conductor 204, including the solenoid 201 which is adapted to actuate the plunger 200 connected on the outer end 199 of the lever 194, whereby the lever is moved on its pivot and causing the inner end 193 thereof to be moved out of contact with the shoulder 192 of the trip cam 188, whereby the one-revolution clutch 158 is caused to engage and drive the main shaft 104 one complete revolution, thereby rotating the cam 153 and causing the low part 154 thereof to contact with the roller 152 on the bifurcated fitting 148 on the upper end of the connecting rod 146', whereupon the spring 151 forces the connecting rod in an upward direction which moves the bell cranks 143 and 143' in a counter-clockwise direction, thus moving the carrier frame 109 outwardly and hence the transparent tabs 120 having the letters 121, including the grid 118 on the inner frame 112, out of contact with the sensitized material. The main shaft 104 in rotating one complete revolution also rotates the crank 103 which in its downward movement pulls downwardly on the rack 96 which drives the feed roller 75

54 through the overrunning clutch 88 in a clockwise direction, whereby after each exposure the required amount of the sensitized material 15 is drawn from the supply roll 25 and fed by the feed roller 54 toward the conventional shearing device of the cutting portion B of the machine between the stationary and movable blades 60 and 61, respectively, thereof. The take-up roller 59 is rotated at a higher speed than the feed roller 54 whereby the take-up rollers 58 and 59' are adapted to take up any slack in the strip of sensitized material from the feed roller 54 to the shearing device and to keep the portion of sensitized material therebetween taut, the tension of which is adapted to be adjusted by screwing the nut 73 on the shaft portion 65 of the take-up roller 59 for adjusting the pressure of the spring 72 for adjusting the amount of frictional contact of the disk 68 with the disk 67 of the friction clutch 66, which clutch 66 can slip when the tension reaches the point for which it is adjusted.

The amount of rotation of the feed roller 54 for feeding the strip of sensitized material toward the shearing device may be controlled for rotating the shaft 100 of the crank 103 with a suitable tool adapted to engage the end 108 of the shaft, whereby the crank pin 98 is adjusted along the shaft carrying the lower end of the rack 96 with it, thus varying the stroke of the rack 96 meshing with the gear 95 of the one-revolution clutch 158, with the amount of adjustment being indicated on the scale 106 by the index 105.

The main shaft 104 in rotating also rotates the eccentrically mounted cam 158 which contacts with the roller 163 on the end of the lever 165, thereby actuating the lever which moves the rock shaft 167 on its bearings 168 which in turn moves the lever 169 connected by the link 171 with the bell crank 173 which in turn actuates the part 177 of the linkage mechanism for operating the cutting blade 61 toward the stationary blade 60 of the shearing device, on the cutting portion C of the machine, to cut the photographic prints 314, Fig. 21, from the strip of sensitized material.

As the position of the shearing device is fixed while the vertical position of the enlarging projection lenses 13 on the lower end of the extensible bellows 11 of the enlarging camera 12 of the photographic projector A changes with the degree of enlargement of the negative image projected onto the strip of sensitized material for producing a print thereof on the sensitized material, and the position of the inner frame 112 on the carrier frame 109 is also changed in a vertical direction so that the center of a projected image may coincide with the center of the grid 118, it is necessary that the distance from the upper edge of the photographic print, Fig. 21, to the blades 60 and 61 of the shearing device is a multiple of the size of a print. This is accomplished by the adjusting mechanism E including the adjusting roller 58 which may be moved around on the feed roller 54 in contact with the strip of sensitized material by unscrewing the nuts 87 on the shaft 84 away from the arms 81, whereby the pinions 86 on the ends of the shaft may be moved in mesh around on the members 82 and, when the roller 58 has been moved to its adjusted position, the nuts 87 are screwed outwardly on the shaft into engagement with the arms 81, thereby preventing the pinions 86 from moving on the members 82, thus holding the adjusting roller 58 in its ad-

justed position. The strip of sensitized material passing over the feed roller 54 and under the adjusting roller 58, then through take-up rollers 59 and 59' is caused to travel a greater distance as the adjusting roller 58 is moved in a clockwise direction on the feed roller 54 and locked in the selected position by the nuts 87. Upon the motor 159 driving the main shaft 104 one complete revolution, the inner end 193 of the lever 194 is caused to engage the shoulder 192 on the trip cam 188 of the one-revolution clutch 158, whereby the clutch is disengaged from the main shaft 104, thus stopping the rotation of the main shaft, with the switch cam 157 having been rotated sufficiently to cause the free end of the switch arm 208 to be released by the lobe 206 on the switch cam 157 and permitting the switch arm 208 to move the micro switches 209 and 209' to an inoperative position, thereby breaking the electrical circuits and returning the apparatus to its original condition.

Upon the switch cam 157 releasing the switch arm 208 for actuating the micro switches 209 and 209' to an open position, the solenoid 244 of the relay 245 has caused the armature 271 to engage the contact 274 so current is maintained back to the negative side of the circuit from the conductor 248 through the armature 271, conductor 275 and conductor 223.

This cycle of operation is automatically repeated in making each photographic print. The shutter 19 may be held open by the solenoid 22 while the conventional electrically operated exposure timing device 213 for the photographic print and the main shaft 104 are stationary by closing the circuit to the lamp 7 through the light switch 215 and opening the circuit to the timing device 213 by the shutter switch 216 and if it is not desired to print the indicia 121 by contact in the margins of the completed photographic prints, the contact switch 217 may be opened, thereby breaking the circuit to the conventional electrically operated contact printing timing device 214, thus making the timing device 214 inoperative.

It will thus be seen that there has herein been provided a novel and useful form of automatically operated photographic printing machine which is well adapted for the purposes indicated. Even though there has herein been shown and described certain features of construction and operation of parts, it is nevertheless to be understood that various changes may be made therein if the changes do not depart from the spirit or scope of the claims.

Having thus described my invention, what I claim as new and wish to secure by Letters Patent is:

1. In a photographic printing machine adapted to produce automatically a plurality of photographic prints of a negative on a strip of sensitized material, the combination of a shutter, a frame having a grid thereon mounted in front of said strip of sensitized material, a photographic projector adapted to project an enlarged image of the negative onto a portion of said strip of sensitized material through the shutter and grid for producing a print of the negative and grid on the sensitized material, means adapted to operate automatically said shutter at predetermined time intervals for exposing the strip of sensitized material and grid to the negative image for producing a plurality of prints of the negative on other portions of the strip of sensitized material, indicia and lighting means mounted on said frame, said indicia designating the lines of the

grid, means for automatically actuating said frame including said grid and indicia at predetermined time intervals into engagement with the strip of sensitized material during an exposure and out of engagement with the strip of sensitized material after each exposure, said lighting means adapted to be operated at predetermined time intervals for printing the indicia on the negative prints during the engagements of said frame with the strip of sensitized material, a shearing device, and means including a feed roller adapted to feed the strip of sensitized material a predetermined distance after each printing of the negative, grid and indicia on the strip of sensitized material.

2. In a photographic printing machine adapted to produce automatically a plurality of photographic prints of a negative on a strip of sensitized material, the combination of a shutter, a carrier frame mounted in front of said strip of sensitized material, a frame movably mounted on said carrier frame, a grid and means including indicia designating the grid lines, and lighting devices mounted on said second-mentioned frame, a photographic projector adapted to project an enlarged image of said negative through said shutter and said frames for producing a print of the negative and grid on a portion of the strip of sensitized material, means adapted to operate automatically said shutter at predetermined time intervals for exposing the strip of sensitized material to the negative image for producing a plurality of prints of the negative and grid on other portions of the strip of sensitized material, means for automatically actuating the carrier frame at predetermined time intervals for moving said second mentioned frame including said grid and indicia into engagement with the strip of sensitized material during exposures of the strip of sensitized material to the negative image and out of engagement from the strip of sensitized material after exposures, said lighting devices adapted to be operated at predetermined time intervals for printing the indicia on the negative prints during the engagement of said last-mentioned frame with said strip of sensitized material, a shearing device, and means including a feed roller adapted to feed the strip of sensitized material a predetermined distance after each printing of the negative, grid and indicia on the strip of sensitized material.

3. In a photographic printing machine adapted to produce automatically a plurality of photographic prints of a negative on a strip of sensitized material, the combination of a shutter, a carrier frame movably mounted in front of the strip of sensitized material, means for automatically actuating said carrier frame at predetermined time intervals toward and away from the strip of sensitized material, a second frame adjustably mounted on said carrier frame, a grid, indicia, and electric lamps carried by said second frame, means connecting said lamps with an electric circuit, a photographic projector adapted to project an image of the negative through said shutter and grid for producing a print of the negative and grid on a portion of said sensitized material, said indicia arranged in spaced formation on the second-mentioned frame and surrounding the negative on the sensitized material, said lamps adapted to be actuated to expose the indicia to the rays therefrom for causing the indicia to be printed on the sensitized material for designating the lines of the grid on the negative print, means adapted to automati-

cally operate the shutter at predetermined time intervals for exposing the strip of sensitized material and grid to the negative image for producing a plurality of prints of the negative on other portions of the strip of sensitized material, means for energizing said electric circuit at predetermined time intervals for lighting said lamps whereby the indicia is printed on the sensitized material during each exposure of the negative image, a shearing device, means for automatically operating the shearing device for cutting the negative prints from the strip of sensitized material, and means including a feed roller for feeding the strip of sensitized material a predetermined distance after each exposure toward the shearing device.

4. In a photographic printing machine adapted to produce automatically a plurality of photographic prints of a negative on a strip of sensitized material, the combination of a shutter, a plate, said strip of sensitized material adapted to move in contact with said plate, a carrier frame, another frame movably mounted on said carrier frame, a grid, lamps and indicia mounted on said inner frame, said indicia and grid adapted to contact with said strip of sensitized material, said indicia adapted to be printed on the sensitized material by said lamps and designating the lines of the grid, a photographic projector adapted to project different enlargements of said negative through the shutter onto the portion of the strip of sensitized material contacting with said plate, a shaft, means including a one-revolution clutch for rotating said shaft one revolution at predetermined time intervals, means connected to be actuated by said shaft for actuating said shutter at predetermined time intervals for exposing the strip of sensitized material to the negative image for producing a plurality of prints of the negative on other portions of the strip of sensitized material, means connected to be operated by said shaft for actuating said carrier frame at predetermined time intervals for moving said second frame including said grid and indicia into engagement with the portion of the strip of sensitized material contacting said plate and to actuate said frames including the grid, indicia and lamps away from said strip of sensitized material, a cam member mounted on said shaft, means adapted to be actuated by said cam member and connected to energize said lamps at predetermined time intervals during contact of said grid and indicia with the strip of sensitized material, a shearing device, means connected to be operated by said shaft for automatically actuating said shearing device for cutting the negative prints from the strip of sensitized material, means including a feed roller for feeding the strip of sensitized material toward the shearing device, and means connected to be actuated by said shaft for actuating the feed roller a predetermined distance after each exposure.

5. In a photographic printing machine adapted to produce automatically a plurality of photographic prints of a negative on a strip of sensitized material, the combination of a support, a shutter, a plate mounted in back of and adapted to be engaged by a portion of said strip of sensitized material, a carrier frame movably mounted in front of the strip of sensitized material, a second frame slidably mounted to move vertically on said carrier frame, a grid, indicia and lamps mounted on said second frame, a photographic projector mounted to move on said support rel-

ative to the strip of sensitized material and including an enlarging camera having an extensible bellows extending vertically downward therefrom, projection lenses and a prism mounted on the lower end of said bellows and adapted to project an enlarged image of the negative through the shutter and grid for producing a print of the negative and grid on the portion of the strip of sensitized material in front of said plate, means for moving the photographic projector relative to the strip of sensitized material for producing any desired enlargement of the negative thereon, means adapted to automatically actuate the extensible bellows in a vertical direction for automatically focusing the camera for any movement of the photographic projector on the support relative to the strip of sensitized material, said indicia mounted in spaced formation on the second frame and adapted to be printed on the strip of sensitized material surrounding the negative print for designating the lines of the grid, said lamps adapted to be energized for exposing the indicia to the rays therefrom for causing the indicia to be printed on the strip of sensitized material, means for automatically operating the shutter at predetermined time intervals for exposing the strip of sensitized material to the negative image for producing a plurality of prints of the negative on other portions of the strip of sensitized material, means automatically actuating the carrier frame toward said plate for contacting the indicia and grid with the portion of the strip of sensitized material engaging said plate during the operation of the shutter for exposing the strip of sensitized material to the negative image, and adapted to actuate automatically said carrier frame away from said plate after the shutter has been actuated to prevent exposure of the strip of sensitized material to the negative image, means for energizing said lamps at predetermined time intervals during the contacting period of said grid and indicia with the strip

of sensitized material whereby the indicia is printed on the strip of sensitized material during each exposure of the strip of sensitized material to the negative image, means for actuating the second frame in a vertical direction relative to any vertical movement of the extensible bellows of the enlarging camera for producing different degrees of enlargements of the negative image on the sensitized material, a shearing device, means for automatically actuating the shearing device at predetermined time intervals for cutting the negative prints from the strip of sensitized material, and automatically operated means including a feed roller for feeding the strip of sensitized material a predetermined distance after each exposure toward the shearing device.

6. In a photographic printing machine adapted to produce automatically a plurality of prints of a negative on a strip of sensitized material, the combination of a frame having a grid and plurality of lamp housings thereon, lamps in said housings, transparent elements having indicia thereon closing one of the ends of said housings, a photographic projector adapted to project an enlarged image of the negative through said grid onto said sensitized material for producing a print of the negative thereon and a print of the grid over the negative print, said lamps adapted to print the indicia on said sensitized material,

means for automatically actuating said frame including said grid, lamp carrying housings and indicia at predetermined time intervals into engagement with the sensitized material during each exposure and out of engagement therefrom after each exposure and means for energizing said lamps at predetermined time intervals for printing said indicia on the sensitized material during engagement of said frame with the strip of sensitized material, said indicia designating the lines of said grid.

GEORGE C. GARRAWAY.
